Primary Examiner — George D. Kirschbaum*Assistant Examiner* — Lillian Embrey(74) *Attorney, Agent, or Firm* — Bayramoglu Law Offices LLC(57) **CLAIM**

The ornamental design for a housing of ultrasonic sensor, as shown and described.

DESCRIPTION

FIG. 1 is a perspective view of a housing of ultrasonic sensor showing my new design;

FIG. 2 is a top view thereof;

FIG. 3 is a rear view thereof;

FIG. 4 is a left side view thereof, a right side view being identical to the left side view;

FIG. 5 is a front view thereof;

FIG. 6 is a sectional view showing the section 6-6 in FIG. 5; and,

FIG. 7 is a sectional view showing the section 7-7 in FIG. 5.
